CLAIM

The ornamental design for a display screen or portion thereof with graphical user interface, as shown and described.

DESCRIPTION

FIG. 1 is a front view of a display screen or portion thereof with graphical user interface according to a first embodiment, showing my new design;

FIG. 2 is a front view thereof according to a second embodiment;

FIG. 3 is a front view thereof according to a third embodiment; and,

FIG. 4 is a front view thereof according to a fourth embodiment.

The outermost broken lines illustrate a display screen or portion thereof. The remaining broken lines illustrate portions of the graphical interface. None of the broken lines form part of the claimed design.
